UNITED STATES PATENT OFFICE.

WILLIAM McCONWAY, JR., OF PITTSBURG, PENNSYLVANIA, ASSIGNOR TO
McCONWAY AND TORLEY COMPANY, OF PITTSBURG, PENNSYLVANIA,
A CORPORATION OF PENNSYLVANIA.

COUPLING.

SPECIFICATION forming part of Letters Patent No. 738,729, dated September 8, 1903.

Application filed December 31, 1902. Serial No. 137,297. (No model.)

To all whom it may concern:

Be it known that I, WILLIAM McCONWAY, Jr., a citizen of the United States, residing at Pittsburgh, in the county of Allegheny and State of Pennsylvania, have invented or discovered certain new and useful Improvements in Couplers, of which improvements the following is a specification.

The invention described herein relates to certain improvements in car-couplers of the Master Car-Builders' or swinging-hook type, and especially to the construction and arrangement of devices or mechanism whereby the locking-block may be supported in unlocking position while the knuckle is closed and the latter may be opened by a further movement of the locking-block beyond its initial unlocking movement.

The invention is hereinafter more fully described and claimed.

In the accompanying drawings, forming a part of this specification, Figure 1 is a top plan view of a Master Car-Builders' type of coupler having my improvements applied thereto. Fig. 2 is a sectional elevation on a plane indicated by the line II--II, Fig. 1, showing the locking-block in locking position. Fig. 3 is a view similar to Fig. 2, showing the locking-block supported in unlocking position where the knuckle is closed; and Fig. 4 is a view similar to Fig. 2, illustrating a modification of the improvement and showing the parts in position to effect an opening of the knuckle.

In the practice of my invention the coupler is of the usual form or construction as regards head 1, knuckle 2, and locking-block 3, except features hereinafter described. In a slot formed in the upper wall of the coupler-head is so arranged a block 4 that the latter may have a lateral movement toward and from the locking-block and also a rotating movement to effect an opening of the knuckle. To this end a slot 5 is formed in the block 4 for the passage of a pin 6, which is supported at its ends by the side walls of the slot in the head. This block is provided with a horn 7, which when the locking-block is in locking position rests against the side of the latter and holds the block 4 back, as shown. As

the locking-block is raised to unlocking position the block 4 will drop forward, the horn entering a notch 8, formed in the side of the locking-block, and by such engagement with the locking-block will support the latter in 55 unlocking position, as shown in Fig. 3. On a further upward movement of the locking-block a toe or projection 9 will engage the horn 7 and cause a rotation of the block 4 on its pin, thereby shifting the arm 10 on the block 4 against the rear wall of the tail of the knuckle, so that by the further movement of the arm the knuckle will be shifted to open position, as shown in Fig. 4. A rib 11, having inclined sides, is so formed on the upper 60 surface of the tail of the knuckle that when the latter is shifted to open position while the locking-block is supported by the horn 7 the rib will strike against the inclined underedge of the projection 15 on the block 4, and thereby rotating the block and its arm 10 so that the latter moves off of its supporting-abutment 13 and the horn 7 and block 4 are forced backward by the movement of the inclined upper edge of the horn along the 65 upper edge of the notch 8, thereby effecting a partial withdrawal of the horn from the notch. When the knuckle has been opened by the lifting of the locking-block, the several parts will assume the positions shown in 70 Fig. 4. As the knuckle is closed the arm 10 will be forced onto its abutment, the block rotating on the pin 6. During this rotation or shifting of the movable block 4 the locking-block will rest on the inclined surface 80 a of the horn, preventing any lateral movement forward into the notch 8, and as the locking-block approaches the upper surface of the tail of the knuckle the horn will be turned out of the notch and its point will slide along the 85 side of the locking-block.

By reference to Fig. 2 it will be seen that the arm 10 of the block 4 rests upon an abutment 13 and forms a pivotal support for the block when the latter is in normal or unlocking position. This pivotal support for the block is at one side of the center of gravity of the block, so that the latter will always have a bias or tendency to drop into locking position. Such movement is, however, pre- 90 95 100

vented by the locking-block, except when the latter is clear of the tail of the knuckle.

In lieu of forming notch or recess in the side of the locking-block a rib 12 may be formed 5 along one edge to hold the block in the position shown in Fig. 2 until the latter is in locking position and the toe 9 formed on the same side of the locking-block, as shown in Fig. 4.

The block 4 is provided with a finger 14, 10 accessible from outside the coupler-head, whereby the block 4 may be shifted to release the locking block or pin without opening the swinging hook or knuckle.

I claim herein as my invention—

15 1. A car-coupler of the Master Car-Builders' or swinging-hook type, having in combination a swinging hook or knuckle, a locking block or pin, a block loosely mounted in the coupler-head and provided with a horn or projection 20 adapted to engage and support the locking-pin when in unlocked position without shifting the hook or knuckle, and having an arm adapted to engage and shift the knuckle on a further movement of the block, substantially as set forth.

2. A car-coupler of the Master Car-Builders' or swinging-hook type having in combination a swinging hook or knuckle, a locking block or pin, a movable block provided with an arm 30 having a pivotal support and having a horn or projection adapted to engage and support the locking-block when in unlocking position without shifting the knuckle from closed position, and to be shifted to release the pin by 35 the closing movement of the knuckle substantially as set forth.

3. A car-coupler of the Master Car-Builders' or swinging-hook type having in combination a swinging hook or knuckle, a locking block or pin, a block movably mounted in the coupler-head and provided with an arm extending back of the tail of the knuckle and having a horn or projection adapted to engage and support the locking-block in unlocking position 45 without shifting the knuckle from closed position and a projection on the locking-block and adapted to engage the horn or projection on the movable block to shift the knuckle to open position, substantially as set forth.

50 4. A car-coupler of the Master Car-Builders' type having in combination a swinging hook or knuckle, a locking block or pin, a block movably mounted in the coupler-head provided with a horn or projection adapted to 55 engage and support the locking block or pin when in unlocking position, and a projection on the tail of the knuckle adapted to engage a toe on the movable block and shift the lat-

ter when the knuckle is opened, substantially as set forth.

5. A coupler of the Master Car-Builders' or swinging-hook type having in combination a swinging hook or knuckle, a locking-pin, a block, having upper and lower pivotal supports about which it successively rotates, and 65 movable upon its upper pivotal support, and having a horn adapted to engage the locking-pin and support it when in unlocked position without shifting the hook or knuckle, and an arm adapted to engage and shift the knuckle 70 on a further movement of the block, substantially as set forth.

6. A car-coupler of the Master Car-Builders' or swinging-hook type having in combination a swinging hook or knuckle, a locking-pin, a 75 movable block, provided with an arm having a pivotal support on the wall of the coupler, and a horn adapted to engage and support the locking-pin when in unlocked position without shifting the knuckle from closed position, and 80 to be shifted to release the locking-pin by the closing movement of the knuckle substantially as set forth.

7. A car-coupler of the Master Car-Builders' or swinging-hook type having in combination 85 a swinging hook or knuckle, a locking-pin, a block having pivotal upper and lower supports about which it successively rotates, and 90 slideable on its upper pivotal support and provided with an arm extending back of the tail of the knuckle and a horn adapted to engage the locking-pin and support it when in unlocked position without shifting the knuckle from closed position, and a hook projection 95 on the locking-pin adapted to engage the horn of the trigger to shift the knuckle to open position, substantially as set forth.

8. A car-coupler of the Master Car-Builders' or swinging-hook type having in combination a swinging hook or knuckle, a locking-pin, a block having upper and lower pivotal supports about which it successively rotates, and 100 slideable on its upper pivotal support and adapted to engage and support the locking-pin when in unlocking position, and a projection on the tail of the knuckle adapted to 105 engage a finger on the block and shift the latter when the knuckle is opened, substantially as set forth.

In testimony whereof I have hereunto set 110 my hand.

WILLIAM McCONWAY, JR.
